UNITED STATES PATENT OFFICE.

HIRAM C. GRAY, OF BUCYRUS, OHIO.

SASH FASTENER.

Application filed April 3, 1922. Serial No. 549,015.

To all whom it may concern:

Be it known that HIRAM C. GRAY, a citizen of the United States, residing at Bucyrus, in the county of Crawford and 5 State of Ohio, has invented certain new and useful Improvements in Sash Fasteners, of which the following is a specification.

The present invention is directed to improvements in sash fasteners, and has for 10 its primary object to provide a device of this character so constructed that it can be easily installed, and when in place will be inconspicuous.

A further object of the invention is to 15 provide a sash fastener so constructed that it will operate to lock the upper and lower sashes in closed positions, or in partially open positions, as desired.

Still another object of the invention is to 20 provide a sash fastener which is operable by a separate key, the structure being such that the key can, when in one position, hold the sash fastener in its inoperative position, and upon removal of the key the fastener 25 will automatically operate to lock the sash.

A still further object of the invention is to provide a sash fastener which is constructed in a compact manner so it can be applied to the window frame without in any 30 way interfering with the sash weights.

With these and other objects in view, as will appear as the description proceeds, the invention consists in the novel feature of construction, combinations of elements and 35 arrangements of parts, and hereinafter to be fully described and pointed out in the appended claims.

In the accompanying drawing:

Figure 1 is a fragmentary front elevation of a window equipped with the fastener, parts being broken away to illustrate the racks.

Figure 2 is a vertical sectional view through one of the fasteners.

Figure 3 is a sectional view on line 3—3 of Figure 1.

Figure 4 is a sectional view on line 4—4 of Figure 2.

Figure 5 is a perspective view of the key 50 guide.

Figure 6 is a detail perspective view of the key.

Referring to the drawing 1 and 2 designate, respectively, the upper and lower 55 sashes, the upper sash having fixed to one of its side rails a rack bar 3, while the

lower sash has fixed to one of its side rails a rack bar 4, the teeth of the rack bars being directed in opposite directions, the purpose of which will later appear obvious.

In order to lock both the upper and lower sashes it is necessary of course to use two fasteners, but since these fasteners are identical in construction, the description of one will suffice for both.

To install the fastener, one side of the window casing 5 is provided with a mortice 6 in which is placed the casing 7, said casing being preferably rectangular in shape. Formed integral with the inner face of the rear wall 8 of the casing is a hollow post 9, and slidably engaging said post is a bolt 10, said bolt having a bore 11 formed longitudinally therein for receiving a portion of the coil spring 12, the other portion of which is engaged in the hollow post 9, there being a guide pin 13 located in said post.

The bolt 10 has riveted thereto a pair of arms 14, said arms being disposed diametrically opposite each other and upon the sides 80 of the bolt 10. The free ends of the arms 14 terminate in lips 15, the purpose of which will appear later.

Journalled in the side walls 16 of the casing 7 is a head 17, said head having connected therewith the lower ends of pins 18, there being two of these pins. The pins 18 are spaced a sufficient distance apart to permit the post 9 to lie therebetween, and since the arms 14 are located on opposite sides of the bolt 10, said pins will be in positions to engage the lips 15. Since the spring 12 tends to force the bolt 10 inwardly it is apparent that the lips 15 will yieldably engage the pins.

A rod 19 is provided, said rod being engaged in a passage 20 formed in the window casing 5 and has its inner end fixed in any suitable manner to the adjacent end of the head 17, whereby when said rod is rotated similar movement will be imparted to the head 17 with the result that the pins 18 will be swung in a direction to slide the bolt 10 into the hollow post 9.

The outer end of the rod 19 is journalled in the key guide 21, said guide comprising an attaching flange 22 and a collar 23, said collar having formed therein at diametrically opposite points, notches 24. The outer end of the rod 19 extends into the collar 23 and has secured thereto a disc 25, said disc having sockets 26 formed therein which are

disposed opposite each other, the purpose of which will later appear.

The key 27 has a circular body 28, and carried by the body are diametrically disposed studs 29, said body being further provided with spaced fingers 30, which are arranged upon the inner face thereof.

Since the rack bars 3 and 4 have their teeth directed in opposite directions it is obvious that either of the sashes 1 and 2 may be locked in their closed positions or partially closed positions as the occasion may require, it being apparent that when the bolt 10 is engaged with the rack 4 that the associated sash cannot be raised until the bolt is withdrawn from engagement with the rack, and it will also be noted that the sash 1 cannot be lowered until the bolt is disengaged from the teeth of the associated rack.

Assuming that the bolt 10 is engaged with the teeth of the rack 4 and it is desired to raise the sash 2 it will be necessary to withdraw the bolt 10 so that the sash and associated rack can be raised, and to do this it is only necessary to place the body 28 of the key in the collar 23 and at which time the fingers 30 will engage the sockets 26 carried by the disc 25. Upon rotating the key 27 the disc 25 will be rotated, thus rocking the rod 19 and swinging the pins 18 rearwardly, which action causes the arms 14 to slide the bolt 10 into the hollow post 9, and at the same time compressing the spring 12. After the body 28 has been rotated a sufficient distance to withdraw the bolt 10 from engagement with its associated rack the studs will drop into the notches 24, thereby holding the rod 19 against reverse movement and the bolt in its withdrawn position. It will be of course obvious that the fingers 30 are

of sufficient length to engage the sockets 26 to impart rotary movement to the disc 25 before the studs 29 drop into the notches 24. Upon removal of the body 28 of the key it will be obvious that the disc 25 can rotate in a reverse direction under the action of the spring 12 as it expands, thus placing the bolt 10 in a position to engage the teeth of the associated rack.

What I claim is:

1. In a sash fastener, the combination with a casing for attachment to a window frame, of a hollow post located in the casing, a bolt slidably engaged in the post, said bolt having arms carried thereby, said arms being provided with lips, a head journaled transversely in the casing and having pins for slidably engaging said lips, a rod associated with the head, and means for rocking the rod to impart similar movement to the pins to cause the bolt to slide in said post.

2. In a sash fastener, the combination with a casing for attachment to a window frame, of a bolt slidably mounted in the casing, arms carried by the bolt, a head journaled transversely in the casing, pins carried by the head for sliding engagement with the arms, a rod associated with the head, a collar fixed to the window frame, a disc located in the collar and fixed to the rod, said collar having notches formed therein, a key having means carried thereby for interlocking engagement with the disc to rock the rod, studs carried by the key body, said disc being held against reverse movement when said studs are engaged in the notches, whereby the bolt is held in its inoperative position.

In testimony whereof I affix my signature.

HIRAM C. GRAY.
